REFRIGERATED SHIPPING CONTAINER

Leonard F. Clerc, Chicago, Ill.

Application August 23, 1941, Serial No. 408,024

16 Claims. (Cl. 62—91.5)

This invention relates to refrigerated containers and particularly to containers in which frozen foods and other commodities may be transported or stored in refrigerated condition.

An object of the invention is to provide a light-weight, inexpensive, shipping container which may be readily collapsed, for return shipment or compact inactive storage, and one which may be quickly set up and placed in refrigerated condition for active service.

Another object of the invention is the provision of a container of the character referred to, which is constructed with interchangeable members which may be readily replaced in the event of damage in transit.

A further object of the invention is the provision of a collapsible shipping container which is adapted to employ dry ice as the refrigerating medium, the container being so constructed and arranged that the sublimation of the dry ice is regulated and temperature control is effected.

It is an object of the invention to provide a device having self-contained refrigerating means, whereby less than car load lots of frozen foods and the like, may be shipped and stored, independent of the usual large scale equipment heretofore required to be employed for such purposes.

Another object of the invention is the provision of a device of the character referred to which is assembled from disconnected sections or panels and held together by straps or other flexible elements, whereby varying degrees of air tightness may be effected between the several sections.

Another object of the invention is the provision of a device of the character referred to which may be employed as a container for shipping perishable merchandise to a destination point, utilizing dry ice as the refrigerant enroute, and at the point of destination a portable mechanical refrigerating machine can be set in to replace the dry ice, and the device can then be employed indefinitely as a storage container.

The foregoing objects and other advantages of the invention will appear as the description proceeds, reference being made from time to time to the accompanying drawings, in which:

Fig. 1 is a perspective view of a device embodying my invention.

Fig. 2 is an enlarged elevation showing the device illustrated in Fig. 1, with the side removed and the top and bottom shells in section.

Fig. 3 is a vertical section taken substantially on the line 3—3 of Fig. 2.

Fig. 4 is a view taken substantially on the line 4—4 of Fig. 2.

Fig. 5 is a view taken substantially on the line 5—5 of Fig. 2.

Fig. 6 is an enlarged perspective view of one of the side walls of the device, with parts broken away to illustrate details of construction.

Fig. 7 is an enlarged fragmentary detail in section, taken substantially on the line 7—7 of Fig. 2.

Fig. 8 is a detailed sectional view of one of the felt covered controlled panels, shown on the bottom of the cooling compartment in Figs. 2, 3 and 4.

Fig. 9 is a modified form of device illustrated in Fig. 1, in which the front wall member is made in two sections and the front flaps of the top and bottom shells are hinged, so that access may be readily had to the interior of the device.

Fig. 10 is a perspective view of a modified form of my device.

Fig. 11 is a front elevation of the device illustrated in Fig. 1, with parts broken away and illustrating the manner in which a portable mechanical refrigerating unit may be installed in place of dry ice as the refrigerant.

Fig. 12 is a view similar to the view shown in Fig. 4, with parts broken away and illustrating a modified form of mechanism for controlling the flow of air and gas in the device.

Fig. 13 is a perspective view, with parts broken away, showing another modified form of my device.

Referring now more particularly to the drawings, it will be understood that in the embodiment herein disclosed (Figs. 1 and 2), my improved shipping container is made up of side walls 12, end walls 13, top 14, bottom 15, top shell 16 and bottom shell 17, all of which are constructed and assembled as hereinafter described.

The shells 16 and 17 are preferably provided with metal reinforcing corners 16a. The side walls 12 (Fig. 6) are preferably constructed of several thicknesses of heat insulating material including an outside layer 18 of substantially hard fibrous material, such as fiber board or the like.

Secured to the inside of the layer 18 by any suitable means, such as gluing or the like, is a second section of insulating material 19 which is assembled in the following manner. Two U-shaped shells of corrugated cardboard 20 and 21 (Fig. 7) are arranged to telescope one another with the corrugations of one shell running at right angles to the corrugations of the second shell, to effect a rigid construction. The void between the shells

20 and 21 is preferably filled with kapok 22 or other effective heat insulating medium. A third section 23 (Fig. 6) is secured to the intermediate section 19 by any suitable means. The section 23 is fabricated and constructed in the same manner as the section 19 hereinabove described. In order to increase the rigidity of the side walls, I provide reinforcing members 24a, which are preferably formed of a corrugated fiber board, bent and rebent to form a plurality of tunnel members as shown in Figs. 7 and 13. The tunnel members 24a of the section 19 are disposed in a vertical position, and the tunnel members 24a of the section 23 are disposed in a horizontal position. The sides of the tunnel members 24a are secured to the inside walls of the shells 21 by means of glue or other suitable means. The voids of the tunnel members 24a are filled with kapok 22, or other effective heat insulating material, as hereinabove described. Secured to the inside of the walls 12 and 13 by means of staples 24, or other suitable means, is a plurality of tunnel members 25. These tunnel members are preferably constructed by bending and rebending a sheet of fiber board as shown in Fig. 6. The tunnel members 23 serve to reinforce the walls 12 and 13, and serve as supports for the floor 26 of the cooling compartment 27 and the storage compartment 28 (Figs. 2 and 3) as is more particularly described hereinafter.

The side walls 12 are also provided on the inside with means 29 (Fig. 6) for supporting a removable shelf 30 (Figs. 2 and 3). The means 29 may be in the form of individual cleats secured by riveting or stapling, or may be formed by inturning the lower edge of one of the layers of fiber board, used in constructing the walls.

The contacting edge surfaces of all of the walls are provided with air tight gaskets 31 (Figs. 6 and 7). The gaskets 31 are preferably made of soft rubber so that varying degrees of compression may be obtained. This is one of the features of the invention as it permits me to control the escape of the CO₂ gas, which is generated in the sublimation of dry ice, when the latter is used as the refrigerant in the device.

It is imperative that the generated CO₂ gas be permitted to escape in a controlled manner. This is accomplished by leaving the seal around the edges of the walls sufficiently loose to permit the gas to escape when its pressure reaches certain limits. I have found that by utilizing this simple expedient I can extend the refrigerating capacities of dry ice over an unbelievable length of time, without having to resort to heavy and cumbersome pressure control means, which would defeat the purposes of a sturdy, lightweight shipping container such as contemplated.

The structure, arrangement and method of assembling my device enables me to take full advantage of these expedients.

In Fig. 7 the construction of the walls 12 and 13 and the manner in which they are assembled and arranged, is better illustrated. In this view it will be seen that the end wall 13 and the side wall 12 are provided with offset edges 32, which engage one another, and between which are positioned the gaskets 31. In this view it will also be seen that the outside layer 18 of the end wall 13 extends around the corner and is bent upon itself, as at 33, and stapled as at 34. The bent portion 33 of the layer 18 is slotted as at 35, through which the straps 36 are extended. The straps 36 extend from the bent portion 33 of the front end member 13 to the bent portion 33 of the

the back end member 13, and tie the device together horizontally. The top 14 and bottom members 15 (Figs. 2 and 3) of the container, are formed in much the same manner as are the side walls 12 and 13 previously described. The top 14 and bottom 15 of the container (Fig. 2) are covered by means of shells 16 and 17 (Fig. 1) whose edges overhang the sides 12 and ends 13, and extend toward each other as at 37, and are slotted as at 38, and are provided with straps 39. The straps 36 and 39 are provided with friction buckles 40 with which they may be tightened to tie the parts together in varying degrees of compression.

The sides of the cooling or dry ice compartment 27 are lined with a plurality of felt covered removable liners 41, which are constructed of the same material and in the same manner as the walls 12 and 13. The floor 26 of the cooling compartment 27 is supported by the tunnels 25 (Figs. 2, 3 and 4), and is provided with cut-outs 42, which communicate with the tunnels 25. Slots 43 are formed in the upper face of the floor 26, and extend beneath the liners 41, and connect the cut-outs 42 with the interior of the compartment 27, so that the CO₂ gas may be carried into the compartment 28 through the tunnels 25. In order to control the flow of CO₂ gas from the compartment 27 to the compartment 28, I provide a novel means which consists of two felt covered panels 44 (Figs. 2, 3 and 8), which overlap one another and which may be extended to cover all or part of the slots 43 to retard the escape of the CO₂ gas into the tunnels 25.

The shelf 30 is provided with tunnels 45 on its upper surface similar to the tunnels 25. The tunnels 45 reinforce the shelf 30 and allow the circulation of air and CO₂ gas below the contents of the compartment 28. In Fig. 9 I illustrate a modified form of container in which the front wall 46 is divided as at 47, and the fronts of the shells 16 and 17 are hinged as at 48, whereby access may more readily be obtained to the interior.

In Fig. 10, I illustrate a modified form of ship, ping container in which I use as the outer shell 50, a carton made of any suitable material, and which is sealed at the corners and provided with a permanent bottom and hinged flaps 51. The interior of the carton 50 is lined with removable walls 52, which are constructed in the manner hereinbefore described and illustrated in Figs. 6 and 7.

In Fig. 11, I illustrate a shipping container similar to the one illustrated in Fig. 1. In this embodiment, however, I illustrate the use of a portable mechanical refrigerating machine in place of dry ice as the refrigerant. In Fig. 11, the floor 53 of the compartment 54 is constructed of heat insulating material and is set in position, and supported by the tunnels 25 as previously described in connection with the member 26 in Fig. 2. The floor member 53 is constructed and reinforced in much the same manner as the side walls previously described. In this embodiment the reference character 55 indicates the housing for the compressor and condenser of the mechanical refrigerating machine, which is positioned on the top of the floor member 53, and the reference character 56 indicates the heat exchange unit of the device, which is suspended beneath the floor member 53. The compressor is driven by a suitable electric motor not shown, which is connected by leads 57 to an outlet 58 provided on the exterior of the container.

In Fig. 12, I illustrate a modified form of mechanism for controlling the flow of CO₂ gas and air between the cooling compartment and the storage compartment. In this embodiment the floor member 59 is supported on the tunnels 25 as previously described. Superimposed on the floor member 59 is a fixed panel 60 and two slidable panels 61 and 62. The panels 61 and 62 are provided with cut-outs 63, which are adapted to communicate with the openings in the tunnels 25. The slidable panels 61 and 62 are joined by means of a link 64 which is pivoted in the center as at 65 and slotted at the ends as at 64a, which slots are adapted to engage pins 61a and 62a. The link 64 may be provided with pointers 66, which are adapted to co-operate with calibrations 67, whereby different degrees of adjustment of the panels 61 and 62 may be registered. The panel 60 is preferably covered with a heat insulating medium such as felt 68a. It will be noted that the tunnels 25 positioned at the ends remain open at all times, whereas the tunnels 25 positioned along the sides may be covered and uncovered by means of the slidable panels 61 and 62, whereby the flow of CO₂ gas and air in the side tunnels 25 may be controlled to effect varying degrees of temperature in the storage compartment.

In Fig. 13, I illustrate another modified form of container which may be constructed in general of three nesting cartons 68, 69 and 70, each of which is provided with a closed bottom and sealed corners. The outside carton 68 is preferably made of a substantially stronger material than the interior cartons 69 and 70. In some applications it may be desired to have the exterior carton made of a fireproof material. The intermediate carton 69 is preferably 1½ inches smaller in all of its dimensions than the outside carton 68, and the inside carton 70 is correspondingly smaller than the intermediate carton 69.

Interposed between the walls of the carton 68 are reinforcing tunnel-like members 71, which are formed as previously described. The tunnel-like members 71 are preferably secured to the outside surfaces of the walls of the carton 69 by gluing, stapling or by other suitable means, prior to the insertion of the carton 69 into the carton 68. The exterior surfaces of the walls of the carton 70 are likewise provided with reinforcing tunnel members 71, which are fastened in a similar manner. The tunnel members 71 which are interposed between the walls of the cartons 68 and 69, are preferably disposed in a vertical position, whereas the tunnel members 71 interposed between the walls of the cartons 69 and 70, are preferably disposed in a horizontal position. This insures a rigid construction for the device. The voids between the walls of the several cartons and the voids in the tunnels are filled with any suitable heat insulating material 22.

The tunnel members 25 are secured to the inside faces of the walls of the carton 70 by stapling or other suitable means and serve the same functions as the tunnels 25 heretofore described, one of the functions being to support the floor 72 of the cooling compartment 73. In all applications of my device I have found that it is preferable to treat the inside surfaces of all of the wall layers and the reinforcing members, the ends of the corrugated layers and the edges thereof, with a suitable moisture-proof material, such as marine glue, tar or asphalt. I also pre-

fer to seal the exposed ends of all corrugated fiber boards which results in the formation of dead air spaces, which serve as additional heat insulators for the walls.

5 The tops of the nested cartons, just described, are closed by means of a top member 74 which is constructed in the same manner as previously described in connection with Figs. 1, 2 and 3. The outside carton 68 is provided with flaps 75 which may be closed in the conventional manner. The container as illustrated in Figs. 1, 2 and 3 is assembled by first placing the bottom 15 in the bottom shell 17, and then introducing one end wall 13 and the side walls 12, leaving the second end wall 13 to be set in position after the shelf 30 is inserted. After the walls and the shelf 30 are in position, the horizontal straps 36 are made fast and the container is ready to be loaded with frozen foods or other perishable commodities. 15 When the storage compartment is sufficiently filled, the floor 26 of the cooling compartment and the control panels 44 are then placed in position on the tunnel members 25. The liners 41 are then set in place and the control panels are adjusted to the proper position to effect the desired temperature control in the storage compartment. The device is now ready for the dry ice or other refrigerant. When the container is charged with the proper amount of refrigerant, the top member 14 is set in position and the top shell 16 is set in place, the vertical straps 39 are then made fast and the device is ready for shipping.

30 Having described my invention, what I claim and desire to secure by Letters Patent is:

35 1. A refrigerating container for the shipment and storage of frozen foods and the like, comprising individual heat insulated walls arranged in contacting relation with one another and defining a compartment adapted to hold dry ice and a storage compartment in communication with the dry ice compartment, the adjacent edges of the walls being separated by compressible sealing elements.

40 2. A refrigerating container for the shipment and storage of frozen foods and the like, comprising individual heat insulated walls arranged in contacting relation with one another and defining a compartment adapted to hold dry ice and a storage compartment in communication with the dry ice compartment, the adjacent edges of the walls being provided with compressible sealing elements, there being means on the outside of said walls for effecting varying degrees of compression on said sealing elements.

45 3. A refrigerating container for the shipment and storage of frozen foods and the like, comprising individual heat insulated walls arranged in contacting relation with one another and defining a compartment adapted to hold dry ice and a storage compartment in communication with the dry ice compartment, top and bottom cap-like members comprising end closures for said container, and flexible elements for holding the walls and cap-like members in assembled relation.

50 4. A refrigerating container for the shipment and storage of frozen foods and the like, comprising individual heat insulated walls arranged in contacting relation with one another and defining a compartment adapted to hold dry ice and a storage compartment in communication with the dry ice compartment, the side walls being provided with vertically disposed reinforcing elements which are secured to the inside thereof and form passageways which communicate between

the dry ice compartment and the storage compartment.

5. A refrigerating container for the shipment and storage of frozen foods and the like, comprising individual heat insulated walls arranged in contacting relation with one another and defining a compartment adapted to hold dry ice and a storage compartment in communication with the dry ice compartment, the side walls being provided with vertically disposed reinforcing elements which are secured to the inside thereof and form passageways which communicate between the dry ice compartment and the storage compartment, there being variable means associated with said passageways for controlling the openings of said passageways.

6. A refrigerating container for the shipment and storage of frozen foods and the like, comprising a plurality of individual heat insulated walls defining a cooling compartment in which dry ice may be used as a refrigerant and a storage compartment, the said walls being in adjustable relation to one another by means of compressible sealing elements interposed between their edges, whereby the rate of escape of CO₂ gas between the walls may be regulated.

7. A device as defined in claim 6, there being additional insulating means in the form of removable liners for said cooling compartment, and reinforcing means carried on the first named insulated walls for connecting the two compartments, whereby air and CO₂ gas derived from the sublimation of dry ice in said cooling compartment may be passed from one compartment to the other.

8. A device as defined in claim 6, there being additional insulating means in the form of removable liners for said cooling compartment, and reinforcing means carried on the first named insulated walls for connecting the two compartments, whereby air and CO₂ gas derived from the sublimation of dry ice in said cooling compartment may be passed from one compartment to the other, and means to control the flow of air and gas to and from said compartments.

9. A shipping container comprising a plurality of individual heat insulated walls held in position by co-operating edge offsets, which prevent their inward displacement and a plurality of flexible members which prevent their outward displacement, the said container having a compartment adapted to carry dry ice, and a compartment for frozen foods or the like, and tunnel means between said compartments arranged to transfer heat.

10. The device defined in claim 9, in which each of the said walls consists of an outside layer of comparatively hard fibrous material and two layers of soft heat insulating material, each of said layers of heat insulating material being encased in a corrugated shell, the corrugations of one shell being positioned at right angles with respect to the corrugations of the adjacent shell.

11. The device defined in claim 9, in which each of the said walls consists of an outside layer of comparatively hard fibrous material and two

layers of soft heat insulating material, each of said layers of heat insulating material being encased in a corrugated shell, the corrugations of one shell being positioned at right angles with respect to the corrugations of the adjacent shell, the side walls of the container having a plurality of parallel tunnel-like members secured to the inside thereof, said tunnel-like members being formed of a sheet of rigid material bent and rebent to form the tunnels.

12. The device defined in claim 9, in which each of the said walls consists of an outside layer of comparatively hard fibrous material and two layers of soft heat insulating material, each of said layers of heat insulating material being encased in a corrugated shell, the corrugations of one shell being positioned at right angles with respect to the corrugations of the adjacent shell, the side walls of the container having a plurality of parallel tunnel-like members secured to the inside thereof, said tunnel-like members being formed of a sheet of rigid material bent and rebent to form the tunnels, the said tunnels being arranged to support the bottom of the dry ice compartment and serve as the inter-communicating means between the compartments.

13. The device defined in claim 9, in which each of the walls consists of an outside layer of a comparatively hard fibrous material and two layers of soft insulating material, each layer of soft insulating material being encased in a corrugated shell, the interior of each shell being provided with reinforcing tunnel-like members, the tunnels of one shell being positioned at right angles with respect to the tunnels of the adjacent shell.

14. A refrigerating container comprising a plurality of individual, heat insulated walls defining a cabinet in which there is a cooling compartment, in which dry ice may be used as the refrigerant, and a storage compartment, there being tunnel like reinforcing elements longitudinally directed and secured to the inside surfaces of the walls of the storage compartment, said tunnel like members communicating with the interior of said cooling compartment and said storage compartment, a shelf comprising a plurality of panels supported by said tunnel like reinforcing members, openings in said panels arranged to communicate with the interior of said tunnel like members, and means to adjust said openings with reference to said tunnel like members.

15. The combination defined in claim 14 in which the panels comprising the shelf are longitudinally adjustable with respect to one another, whereby the openings in said panels may be adjusted with reference to said tunnel like members.

16. The combination defined in claim 14 in which the panels comprising the shelf are longitudinally adjustable with respect to one another, whereby the openings in said panels may be adjusted with reference to said tunnel like members, and a cross-bar pivoted to said panels, and means on said cross-bar cooperating with means on one of said panels for indicating the degree of adjustment of said panels.

LEONARD F. CLERC.
